UNITED STATES PATENT OFFICE.

JOHN SMITH, OF MIDDLETOWN, OHIO, ASSIGNOR TO THE AMERICAN IRON ROOFING COMPANY, OF MIDDLETOWN, OHIO.

METALLIC BUILDING MEMBER.

1,121,679.

Specification of Letters Patent. Patented Dec. 22, 1914.

Application filed January 17, 1914. Serial No. 812,841.

To all whom it may concern:

Be it known that I, JOHN SMITH, a citizen of the United States, residing at Middletown, Butler county, Ohio, have invented 5 certain new and useful Improvements in Metallic Building Members, of which the following is a specification.

This invention pertains to the construction, from sheet metal, of a metallic building member designed principally for use in 10 the construction of wall-work. While my invention is not limited in the respect to be mentioned, it has been devised with special reference to the construction of the metallic 15 walls of granaries.

The invention will be readily understood from the following description taken in connection with the accompanying drawing in which:—

20 Figure 1 is an elevation of a wall, assumed as a metallic wall, embodying my improved studding: and Fig. 2 a horizontal section of the same. Fig. 2 is on a very much larger scale than Fig. 1, and in Fig. 1 the distance 25 between the studs is illustrated as being very much less in proportion than would generally be the case in practice.

In the drawing:—1, indicates any suitable 30 foundation to support the structure which is to embody my improved studding: 2, the studs, generally considered, which rest upon the foundation and are arranged in series, circular or straight, and spaced apart such 35 distance as is deemed preferable: 3, the plain wall-members arranged between the studs and having their vertical edges engaging within the body of the studs, these wall-members being flat or horizontally curved according to whether the structure is 40 to be circular or rectangular: 4, an empty wall-space, illustrated in Fig. 1: 5, sheet-metal bent up to form the stud and engage the interior and exterior surfaces of the edges of the wall-members 3 and to form a 45 stiffening rib: 6, the opposite edge portions of the sheet metal forming the stud, the outer extremities of these edge portions engaging one surface of the wall-members 3: 7, portions of the stud material bent at right 50 angles to portions 6 and crossing the plane of wall-members 3: 8, portions of the stud material bent outwardly from portions 7 and extending along that side of the wall material opposite stud portion 6, the outer 55 extremities of these stud-portions 8 engag-

ing that face of wall material 3 opposite the outer extremities of stud portions 6: 9, portions of the stud material in prolongation of stud portions 8 but bent back upon stud portions 8, and toward each other: and 60 10, stud-material, folded to form a double thickness and forming a prolongation of portions 9, this portion 10 forming a strengthening rib upon the side of the stud opposite portions 6.

In producing this sheet metal stud, a sheet metal strip of proper width may be taken and given its middle fold to form the rib 10, portions 9 being bent outwardly from opposite sides of the rib, the portions 8 being 65 then folded inwardly to give the double thickness, 8—9, bends 7 then being produced from the portions 8, opposite the rib 10, the portions 6 being bent outwardly from the 70 portions 7.

The distance between the outer extremities of portions 6 and 8 will be such as to accommodate, with suitable gripping effect, the main wall material which is to fill the spaces between the studs. In the case of the main wall material being sheet metal, which will generally be the case, the outer extremities of portions 6 and 8 may, if desired, be in contact with each other, so that the insertion 75 of the sheet forming the main wall portion will require some springing apart of these extremities and produce more or less gripping effect upon the wall-material. It is my preference that the distance between stud portions 6 and 8 be more than the thickness 80 of wall material which the stud is to receive, and that the outer extremities of these portions 6 and 8 be bent toward each other so as to form converging jaws for the gripping 85 effect of the main wall material, the outer side extremities of the stud thus being provided with wall-receiving jaws, so to speak.

An inspection of Fig. 2 will make it evident that wall-members 3 may be curved or straight, according to whether the structure 90 is to be circular or rectangular, and also that, given a stud of the section illustrated in Fig. 2, its side members may be separated from each other, the union of portions 10 acting as a hinge so that the side members of the studs may be either in the same plane or 95 at angular relationship to each other.

I claim:—

A metallic building member consisting of an integral strip of sheet metal bent at its 100

center of width to form a forwardly outstanding rib of double thickness, a portion bent sidewise from each of the thicknesses of said rib and at right angles thereto, said 5 sidewise bent portions being then folded inwardly to the plane of said rib to form at each side of the rib a clamping member of double thickness, the inner thickness of said clamping members being then bent rear-
10 wardly in the plane of the rib and then bent outwardly sidewise, the edges of the metal resulting from the last bending coming opposite the extremities of said clamping mem-

bers and forming second clamping members, said first-mentioned and second clamping 15 members being adapted to receive a sheet of material between them, and the outer portions of the clamping members being bent into convergence with each other so as to engage the sheet only at the extremities of 20 the clamping members, combined substantially as set forth.

JOHN SMITH.
